(57) **CLAIM**

The ornamental design for car headphone with wheel rim, hub, and spokes, as shown and described.

DESCRIPTION

FIG. 1 is a side perspective view of car rim headphone with wheel rim, hub, and spokes showing my new design.

FIG. 2 is a front elevation view thereof, with a rear elevation view being a mirror image of the front elevation view.

FIG. 3 is a left elevation view thereof, with a right elevation view being a mirror image of the left elevation view.

FIG. 4 is a top plan view thereof; and,

FIG. 5 is a bottom plan view thereof.

The broken lines shown in the drawings depict portions of the car headphone with wheel rim, hub, and spokes that form no part of the claimed design.
